UNITED STATES PATENT OFFICE.

ULYSSES GRANT CAVE, OF LOUISVILLE, KENTUCKY, ASSIGNOR TO MULTIPLEX SALES REGISTER COMPANY, OF LOUISVILLE, KENTUCKY, A CORPORATION OF SOUTH DAKOTA.

AUTOGRAPHIC REGISTER.

1,263,037.

Specification of Letters Patent. Patented Apr. 16, 1918.

Application filed June 29, 1914. Serial No. 848,047.

To all whom it may concern:

Be it known that I, ULYSSES GRANT CAVE, a citizen of the United States, resident of Louisville, in the county of Jefferson and State of Kentucky, have made a certain new and useful Invention in Autographic Registers; and I declare the following to be a full, clear, and exact description of the same, such as will enable others skilled in the art to which it appertains to make and use the invention, reference being had to the accompanying drawings, and to letters or figures of reference marked thereon, which form a part of this specification.

15 Figure 1 is a plan view of the register, an end plate being shown in dotted lines as turned pivotally.

Fig. 2 is a side view of the casing with one side thereof removed, one cover part for 20 a platform plate being removed, one end plate being shown as turned to one side, and paper being shown in dotted lines.

Fig. 3 is a detail side view of one of the platform cover plates.

25 Fig. 4 is a detail section on the line 4—4, Fig. 5.

Fig. 5 is a detail section on the line 5—5, Fig. 4.

Fig. 6 is a detail perspective view of a 30 platform cover.

Fig. 7 is a detail perspective view of a supply spindle.

Fig. 8 is a detail perspective view of a toothed guide roller.

35 Fig. 9 is a detail perspective view of a record spindle, showing the end of the paper in engagement therewith.

Fig. 10 is a fragmentary longitudinal section of the paper file slip or check in 40 duplicate and as pinned together by the engaged walls of the perforations.

The invention has relation to autographic registers for use in registering or recording memorandums and sales in mercantile and 45 other transactions, having for an object to insure a positive feed of the paper without back slip and to pin the paper slips or sheets upon which the items are registered together by the paper material thereof. The 50 invention consists in the novel construction and combinations of parts, as hereinafter set forth.

In the accompanying drawings, illustrating 55 the invention, the numeral 1, designates a frame or casing having a platform plate

2, and two rotary spindles 3 and 4, designed respectively to receive the paper supply or feed roll 5, of paper, and for winding of the paper to constitute the record roll 6, the paper passing from the supply roll outwardly, longitudinally over the platform plate, the upper sheet or sheets of paper 7, 7', passing then over a roller 8, located usually at the rear end of the platform plate and carrying an annular series of 60 pointed teeth or projections 9, for engagement with the said outer sheet or sheets, to insure a positive feed thereof without back slip, and thence out of the casing through a transverse slot 9', thereof. The lower sheet 70 or sheets of paper 10, preferably also pass over this roller, in engagement with the points thereof, and thence inwardly to the record spindle, to which they are made fast for winding.

75 It is preferred that a cover 11, shall be provided for the platform plate, said cover having an opening 12, to expose the paper passing over the platform plate, and in order to facilitate the manipulation of the 80 paper over and around the pointed roller and through the transverse slot 9', the cover plate 11, and the end plate 13, of the casing, are usually both movable with relation to the casing and to each other.

85 The cover plate is made entirely detachable, and has connection with the casing usually by means of a lateral flange 14, having a lower hook end 14', engaging in a seat 14'', of the casing, a binding screw 15, of 90 the casing having its stem engaging an open-bottom notch seat 15' of said end, and its head in clamping engagement with the side of the hook end, said plate having at its opposite side a pivotal latch 16, located under the platform plate and engaging the end of a rod 21, hereinafter referred to, to hold the cover plate down at that side.

95 The end plate is usually pivoted to the casing at 17, so that it may be turned to one 100 side, out of the way, when the paper is being adjusted. The transverse slot 9', of the casing, through which the upper sheets of paper pass out of the casing, is located between the upper edge of the end plate 105 and the rear end of the cover plate, and the lower paper sheets, having been adjusted around the pointed roller and made fast to the record spindle, and the end plate being turned back to normal position, the upper 110

paper sheets are engaged with the points of the pointed roller, (the end plate being held in normal position usually by headed studs 18, under which the edge of the plate 5 engages) the upper paper sheets are then passed over the top edge of the end plate (said top edge being provided with a bent flange 19 to provide a broader bearing surface for the paper sheets), after which the 10 cover plate is readjusted to position.

A spring pressure device 20, usually carried by the cover plate and coöperating with the points of the feed roller, is employed to press the outer paper sheets in engagement 15 with the points of the roller.

The platform plate is usually slidably engaged with transverse rods 21, of the casing, said rods and the record and supply spindles being carried by a stationary side 22, of 20 the casing, so that when the other removable side 23, of the casing, is detached, the paper rolls may be inserted in place or removed as may be required and the platform plate may be slid out and in.

25 When the side of the casing is removed, the cover plate removed, and the end plate turned to one side, the interior of the casing is effectually opened for manipulation and adjustment of the paper and rolls.

30 The points of the roller, as stated, will cause the upper sheets of paper to feed positively, without back slip, when the record roll spindle is rotated by suitable means, usually a crank 22' thereupon, to feed the 35 upper paper sheets and wind the lower paper sheets upon the record roll. And these points will also pin the upper sheets of paper together, so that when the slip is torn off at the straight edge 23', both the upper 40 and lower slips will be perforated longitudinally, as at 24, the walls or edges of the perforations of the lower slip being slightly offset into engagement with the perforations of the upper slip, the two slips being thereby 45 secured or pinned together by the paper of the slips.

And inasmuch as the upper and lower paper sheets are first flattened out in their passage over and from the platform plate 50 to the pointed roller, and issued in flat form from the pointed roller of the machine, the paper slips torn off at the straight edge and so pinned together are, by the paper lock or pinning, held in flat form and prevented 55 from curling or bending, being thereby more easily handled.

Carbon paper is used between the paper sheets, the carbon roll being usually wound suitably upon a spindle or rod 25, and engaged with spring devices 26, secured within a seat 28, of the casing. The carbon paper passes transversely over the platform plate, between the paper sheets, and at the opposite side thereof, is suitably fixed in position, preferably by passing the ends of the

carbon paper under a lateral flange 29, of the cover plate and turning up a pivoted channeled clasp 30, in engagement with the carbon ends and with the said lateral flange.

When new carbon is required the pivoted 70 clasp is turned down, the carbon ends grasped and pulled to unwind fresh carbon, the ends of the fresh carbon secured in the manner stated and the worn part torn off at the upper straight edge of the clasp.

The paper supply spindle has suitable gripping means for the interior walls of the tubular spool 31, carrying the supply paper roll, usually radial spring arms 32, of said spindle.

The end of the lower or record paper sheet is made fast to the record spindle by suitable means, preferably a spring grooved clasp 33, coöperating with the rounded or cylindrical spindle and between which the 85 end of the paper sheet is passed or slid and held.

The casing is provided with a plurality of sides, preferably four in number, the parts described being furnished for each 90 side.

What I claim is:

1. In an autographic register, a means for pinning paper sheets together by the paper material thereof, consisting of a roller provided with an annular series of slender pointed teeth, and a pressure device coöperating with and operating within the lines of said teeth.

2. In an autographic register, a casing 100 having a platform plate, a paper supply spindle, and a roller located near one end of said plate and provided with an annular series of slender pointed teeth, capable of pinning paper sheets together by the paper 105 material thereof, and a pressure device coöperating with and operating within the lines of said teeth.

3. In an autographic register, a casing having a platform plate, a paper supply 110 spindle, a record spindle, and a roller located near one end of said plate and provided with an annular series of slender pointed teeth capable of pinning paper sheets together by the paper material thereof, a supply roll of 115 paper having three overlying paper sheets passing over the platform plate, over said roller into engagement with said teeth, a pressure device coöperating with and operating within the lines of said teeth, the two 120 upper sheets so pinned together passing out of the casing, and the lowermost sheet passing from said roller to the record spindle.

4. In an autographic register, a casing having a platform plate, a paper supply 125 spindle, a roller located near one end of said plate and provided with an annular series of slender pointed teeth capable of pinning paper sheets together by the paper material thereof, said platform plate being 130

removable to expose said roller at the top and carrying a pressure device coöperating with and operating within the lines of said teeth, and means for exposing said roller at the end thereof comprising a movable end plate for the casing.

5. In an autographic register, a casing having a platform plate, a paper supply spindle, a roller located near one end of said plate and provided with an annular series of slender pointed teeth capable of pinning paper sheets together by the paper material thereof, said casing being provided at one side with a seat, a carbon roll holder in said seat, and a platform cover plate removable to expose said roller at the top and carrying a pressure device located and operating within the lines of said teeth, said plate having at one side a downturned flange, and 20 a pivotal clamp member for the end of the carbon sheet.

6. In an autographic register, a casing having a platform plate, a paper supply spindle, a roller located near one end of said plate and provided with an annular series of slender pointed teeth capable of pinning paper sheets together by the paper material thereof, a removable cover for the platform plate carrying a pressure device located and 25

operating within the lines of said teeth, said casing having a seat at one side, and said cover having at one side a hook projection engaging said seat, and a clamp screw engaging the casing and said hook projection, said cover having at the other side a pivoted latch device.

7. In an autographic register, a casing having a platform plate, a paper supply spindle, a record spindle, a roller located near one end of the platform plate and provided with a series of long slender pointed teeth, a removable cover for the platform plate having at one side a hook projection for engagement with a clamp screw and at the other side a pivoted latch and a carbon sheet clamp device, and means carried by and removable with said cover, coöperating with said roller and located and operating within the lines of said teeth for perforation of the paper sheets and to prevent backslip thereof, and a pivoted end plate for said casing adjacent to said roller.

In testimony whereof I affix my signature, in presence of two witnesses.

ULYSSES GRANT CAVE.
